UNITED STATES PATENT OFFICE.

DORIN CORBETT DOWDY, OF HUNTINGTON, WEST VIRGINIA.

RIVET-HOLDING DEVICE.

1,105,892.

Specification of Letters Patent.

Patented Aug. 4, 1914.

Application filed January 25, 1913. Serial No. 744,118.

To all whom it may concern:

Be it known that I, DORIN CORBETT DOWDY, a citizen of the United States, residing at Huntington, in the county of Cabell and State of West Virginia, have invented new and useful Improvements in Rivet-Holding Devices, of which the following is a specification.

This invention relates to the class of riveting appliances and more specifically to a rivet holder adapted for use in connection with boiler rivets, wherein the space afforded for such operation is very limited.

The primary object of my invention is to provide a rivet holding device of such novel and peculiar construction as to effectively hold within a boiler tube, fire-box or the like, a heated rivet, in such a manner as to prevent slipping thereof while the rivet is being pounded by any other suitable means.

Another object of my invention is to provide a device of this character which is not only simple in construction but reliable and efficient in operation, and one which can be manufactured and placed upon the market at a minimum cost.

Heretofore, it has been necessary to use what is commonly known as a "wedge-bar" for holding heated rivets in proper place during the construction of a boiler, and upon practical application, it has been found that such a tool very often slips allowing the rivet to become cool, thereby requiring that same be cut-out and replaced, which is not only expensive but exceeding troublesome; while, whereas, with my device these and other objectionable features are thoroughly overcome and the rivet is rigidly held in proper place until the riveting operation has been entirely completed, whereupon the device is removed.

With the above and other objects in view, my invention relates to such details of construction and in the arrangement and combination of the several parts as will be hereinafter fully described and specifically pointed out in the appended claims.

In describing my invention in detail reference will be had to the accompanying drawings wherein like characters denote like or corresponding parts throughout the several views, and in which:—

Figure 1 is a side elevation partly broken away showing the device complete. Fig. 2 is a section on line *a*—*a* of Fig. 1, and Fig. 3 is an elevation of one end of the device.

In the accompanying drawings wherein is illustrated the preferred form of my invention, the numeral 1 designates a suitable air receptacle or compression chamber, covered at its forward and rear ends by caps 2 and 3 respectively, the latter having an air inlet pipe 4 in conductive relation therewith. A valve 5 of the three way turning plug type is provided in the inlet pipe whereby air may be admitted to the chamber and exhausted therefrom when occasion requires.

The caps above referred to have provided thereon diametrically opposite ears 6 through which are journaled parallel extending rods 7, the latter having head portions 8 formed at their rear ends, while eyelets 9 are provided at their forward extremities. The length of the rods is considerably greater than the distance between the caps so that the eyelets 9 are disposed slightly beyond one of the caps thereof.

A pair of spaced apart parallel extending arms 10 are provided which are formed integral at their rear ends as shown at 11, they being held in rigid relation with the cap 2 through the coöperation of a transverse pin 11' carrying head portions 12, with the eyelets 9 and rods 7.

Operative within the air chamber is a plunger head 12', from which projects a piston rod 13, the latter extending through the cap 2 and body portion of the arms 10 and disposed between the arms as is clearly shown. A coil spring 14 is also provided for the purpose of normally holding the plunger in its rearmost position within the chamber, so that when air under pressure is admitted to the cylinder, the piston rod will be forced between the arms as is obvious. The forward ends of the arms are formed substantially wedge-shaped as shown at 15, while a substantially frusto-conical shaped member is disposed therebetween and has rigid connection with the forward extremity of the piston rod. It is now apparent that when the piston rod is forced forward between the arms, the outer extremities of the latter will be forced apart so that the wedging action occurs. For the purpose of engagement with a rivet 17, a head portion 18 is provided upon one of the arms and has a slightly concaved face as is apparent.

In the operation of my invention in connection with the riveting in boilers of the ordinary type, the device is first disposed between the tubes of the boiler, the arms being

disposed in engagement with one of the tubes and the head of a rivet, the latter extending through the crown sheet or any structure connected therewith. Air and pressure is then introduced into the cylinder which will move the piston rod from its original position and consequently force the arms apart so that the rivet is securely held in place during the action of the rivet machine.

10 While I have described my invention as being used in connection with a boiler, it is apparent that I do not limit myself to this specific use and that it can be employed in connection with any structure whatsoever if 15 occasion requires.

I desire it to be understood that I may make slight changes in the construction and in the arrangement and combination of the several parts, provided, however, such 20 changes fall within the scope of the subjoined claims.

Having thus fully described my invention, what I claim as new and desire to secure by Letters Patent, is:—

25 1. In a device of the character described, the combination with an air chamber and a piston operating therein, of a rod operable through movement of said piston, arms arranged in parallel relation and in line with the movement of said rod, and means upon 30 said rod and engaging said arms for forcing

the same apart, as and for the purpose set forth.

2. In a device of the character described, the combination with an air chamber having a piston mounted therein, of a pair of yieldable arms arranged in parallelism to extend from one end of said chamber, the said arms being wedge-shaped at their outer extremity, and a rivet holding element upon one of the 40 said arms, means operable through movement of said piston and engageable with said arms for forcing the wedge-shaped extremities apart, as and for the purpose set forth. 45

3. In a device of the character described, the combination with an air chamber and a piston operating therein, of a rod operable through movement of said piston, arms arranged in spaced relation and in line with the movement of said rod, said arms being wedge-shaped at their outer extremity, a rivet holding element upon the extremity of one of said arms, of a wedge-shaped head formed upon the free end of said rod and 50 engageable with the wedge-shaped extremities of the respective arms for forcing the latter apart, as and for the purpose set forth. 55
